Charles E. Cowdin
INVENTOR

UNITED STATES PATENT OFFICE

CHARLES E. COWDIN, OF PORTLAND, OREGON, ASSIGNOR TO COWDIN COMPANY, A CORPORATION OF OREGON

FOLDING TABLE

Application filed December 23, 1929. Serial No. 416,023.

This invention pertains to improvements in folding tables and has primarily for its object to provide a simple, inexpensive and efficient brace for rigidly locking the legs in 55 operative and closed positions.

A further object of the invention is to provide a slidable construction to guide the free end of the brace between the open and closed position.

10 With the above and other objects which will hereinafter appear and be shown and described, it is understood that such changes in the precise method here outlined and disclosed may be made as come within the scope of the 15 claims.

The accompanying drawings illustrate the construction at the present time preferred from a practical and manufacturing standpoint. The design is especially adapted to be 20 made from commercial material by die methods.

In the drawings Figure 1 is a perspective view of the brace and slide attached to a leg and table top and holding the leg locked perpendicular to the plane of the table.

25 Figure 2 is a section of parts A and B taken through as of line X—X in Fig. 1.

Figure 3 is a view showing the shape preferred for the notch H in part B.

30 Figure 4 is a plan view of the invention showing the leg closed and locked in this position.

Figure 5 is a cross section shown as line Z—Z in Figure 1.

35 It will be evident that this invention may be applied with suitable modifications to tables of any number of legs, and may be used at other places and on other devices where these characteristics are needed.

40 The leg G is secured pivotally to the table at F in any suitable manner and the brace A is also pivotally held to the leg at C and at this joint is stressed in such a manner that it tends to spring in the direction of the arrow 45 T. Such spring action tends to insert, lock and retain the brace A in the slots or notches H and I when brought to these positions along the slide.

The leg G is arranged to fold against the 50 underside of the table-top, usually in parallel

with one of its marginal edges. The slide-bar B is secured to the underside of the table in parallel with the respective leg when thus folded and disposed in spaced relation thereto, as shown in Fig. 4, to admit of the brace A 55 lying therebetween with sufficient amplitude for the retraction of the brace from its engagement with either of said notches H or I.

Referring to Figure 3 it will be noticed that the notch H has a rounded or otherwise chamfered corner at O and that a slight taper to the notch is preferred and by reference to Figure 2 it will be seen that the notch H is cut at an acute angle through the slide bar B; notch H, however, is also practical if cut at right angles to the normal surface of slide bar B and may be so constructed.

Referring to Figure 5, C is a bolt or screw or other suitable pivot; N is a washer, A is a section of the brace, Q is a spacing bushing 70 or washer adapted to take the clamping action of C without clamping A. M is a washer and G is a partial section of the leg.

It will be evident that when the set, or spring tension in the direction of the arrow T is reacted and transmitted by the joint shown at C that the washers N and M will take the stress and wear. The offsets shown at L and K are for the purpose of raising the bar from the table so that portion of A, which is shown bent at right angles and slotted to receive slide bar B, may slide along without friction or obstruction.

The locking of the brace in the slide bar at the open and closed positions is automatic 85 and the release is a matter of a pressure in a direction opposite of the resilient urge or spring pressure aforementioned.

It will be evident that all wear is taken by metallic surfaces and that a rapid and automatic locking system is established that is rigid and practical. It will also be noticed that this invention can be adapted to that type of table in which the legs fold to the center 90 with facility as the slide bar B may be placed in any direction and by proper blocking beneath it, at any height from the table to allow one system of legs to cross and fold under another.

Changes in detail not affecting the spirit of 100

this invention may be made such as change in the joint at C, a change in mounting methods of the slide bar B and other changes.

Having thus clearly described my invention I claim:

1. A folding table, consisting of a top, a plurality of legs pivotally connected with said top to fold in parallel with the underside of said top, a slide-bar associated with each said leg rigidly secured to the underside of said top and in parallel, spaced relation with the respective leg when in folded condition, said slide-bars each having a pair of notches formed in its lateral side proximate to the respective leg, and a brace pivotally connected to each said leg at one end and formed with an aperture at its opposite end through which said slide-bar is extended, each said brace being in resilient engagement with said slide-bar to enter and be retained in said notches in the open and folded condition of the leg respectively.

2. A folding table, consisting of a top, a leg pivotally connected thereto, and arranged to fold in parallel with the underside of said top, a slide-bar rigidly secured to the underside of said top in parallel and in spaced relation with said leg when in folded condition, said slide-bar having a pair of spaced V-shaped notches in its lateral edge adjacent said leg, a brace pivotally connected at one end to the side of said leg proximate to said slide-bar and having a slotted hole in its other end through which said slide-bar extends, and means associated with the pivotal mounting of said brace for exerting spring-tension upon the brace urging the brace into sliding engagement with the slide-bar and to provide for the resilient seating of the brace within said notches, respectively, in the open and closed positions of the leg.

3. In a folding table, a leg pivotally connected to the underside of the table-top and adapted to be folded into close relation with said underside, a slide-bar secured to said underside of the table-top in parallel and in spaced relation to said leg when in folded condition and having a notch on its lateral side proximate to said leg, and a brace pivotally mounted on said leg and engageable at its opposite end with said slide-bar and to seat in said notch, said brace being formed with an offset towards said slide-bar adjacent its outer end whereby the brace may lie between the slide-bar and the leg when in folded condition and admit of the brace being disengaged from said notch.

4. In a folding table, a leg pivotally connected thereto, a slide-bar rigidly mounted upon the underside of the table-top having a V-shaped notch upon its inner lateral edge, a brace pivotally mounted at one end upon a side of said leg opposing said slide-bar and formed with an approximately right-angled bend at its opposite end, said angular portion

having a slotted hole through which said slide-bar extends, and means to resiliently urge said brace into sliding contact with said slide-bar whereby the brace will be caused to enter said notch to retain the leg in open condition.

CHARLES E. COWDIN.
